UNITED STATES PATENT OFFICE.

FRANK W. BURPEE, OF SOUTH BELLINGHAM, WASHINGTON.

CAN-COVER-SEAMING MACHINE.

1,224,358.

Specification of Letters Patent.

Patented May 1, 1917.

Application filed October 11, 1915. Serial No. 55,296.

To all whom it may concern:

Be it known that I, FRANK W. BURPEE, a citizen of the Dominion of Canada, residing at South Bellingham, in the county 5 of Whatcom and State of Washington, United States of America, have invented certain new and useful Improvements in Can-Cover-Seaming Machines, of which the following is a specification.

10 This invention relates to a can cover seaming machine of the double spindle class, wherein the seaming of the cover to the upper edge of the can is effected in two operations by separate rotatable heads each 15 having opposed seaming rollers rotatably carried in the head.

Many machines have been designed to effect the closure of the edges of a can cover upon the outwardly flanged edges of the can 20 body in the same general manner as is here set forth, but, owing to the multiplicity of movements necessary in effecting the several operations, the great majority of machines designed for this object are complicated in their mechanism and therefore liable 25 to derangement and expensive to maintain. This is largely due to the extremes of speed required for the various operations: from the high speed of the rotatable 30 seaming head to the relatively low speeds of the mechanisms required to operate the can feed, etc.

The machine, which is the subject of this application, has been designed to simplify 35 the mechanism and enable all movements of the machine to be derived from a primary or first motion shaft, and to accomplish these results, while maintaining a high rate of output and efficient seaming of the 40 covers.

The invention also comprises an improved means for closing the seaming rollers on the edges of the cover and can body and a means whereby the release of a can cover 45 from the cover magazine is timed cooperatively with the delivery of a can body to the turret by which they are carried from the line of feed and discharge, to and from the seaming heads.

50 There are other incidental features of improvement to which attention will be called in the course of the following specification which particularly describes the machine, reference being made to the drawings by 55 which it is accompanied, in which:

Figure 1 shows the upper part of a can

body and its cover as delivered for the seaming operation.

Fig. 2 is an enlarged detail of the seam as closed, the seaming being effected in two 60 operations.

Fig. 3 is a front elevation of one half of the machine with the can cover magazine removed and a vertical section through the spindle of the primary or right hand seam- 65 ing head and the can body lift.

Fig. 4 is a side elevation of the machine complete.

Fig. 5 is an enlarged detail being a section across the aperture of the cover de- 70 livery plate.

Fig. 6 is a plan of the lower part of the machine, being a section on the line 6—6 in Figs. 3 and 4.

Fig. 7 is a sectional plan of the upper 75 part of the machine showing the gearing by which the several main shafts of the machine are driven from the first motion shaft.

Fig. 8 is an elevation and vertical sec- 80 tion to an enlarged scale of the seaming head and correlated parts.

Fig. 9 is a sectional plan of the same on the line 9—9 in Fig. 8.

Figs. 10, 11, 12 and 13 are enlarged details of a seaming roller and the manner of 85 mounting it in its stem.

Fig. 14 is a plan of the Geneva movement of the can holding turret.

Fig. 15 is a detail sectional view of a por- 90 tion of the machine.

In these drawings 2 represents the frame of the machine and 3 the first motion shaft from which all the movements of the machine are derived. This shaft 3 drives by 95 bevel wheels 5 an intermediate vertical shaft 4.

On the upper end of this intermediate shaft 4 is secured a pinion 7, the teeth of which mesh with those of a wheel 8 secured on the upper end of each of two vertical cam shafts 9 and 10. Each of these cam shafts 100 effects the rise and fall of its adjacent seaming head spindle and the rise and fall of the can body plunger, and in addition one of these shafts 9 operates the spacing mechanism of the feed and the other 10 the rotation of the turret.

On the lower end of the intermediate shaft 4 is secured a gear wheel 11, the teeth of which mesh with teeth 12 cut in each of the two vertically disposed hollow spindles 13 of the rotating seaming heads 17 by which 105 the covers of the cans are effectively closed.

on the flanges of the can bodies, the complete operation of seaming the covers on the can bodies being effected in two operations by the two heads.

5 Each spindle 13 is carried in oppositely angled roller bearings 14, adjustably mounted in a bearing casing 15 which is vertically movable in a bearing 16 in the frame 2 so that endwise movement of the bearing casing effects corresponding endwise movement of the spindle 13 and its head 17. The lower end of the spindle or head 17 is of wedge form tapered equally on each side from the axis of the spindle, and the angled sides of 10 the head are grooved, as at 6, to receive the rectangular stems 18 on the ends of which the seaming rollers 19 are rotatably mounted. These stems 18 are endwise movable in their grooves in the head each of which is 15 provided with a cover plate 21. In the secondary or finishing head the securing screws of its cover plates 21 are located in the upper ends of the plates and the lower ends of the plates are reduced in thickness that they may 20 act as springs and yield outward to permit the rollers to pass over the multiple thickness of metal at the longitudinal seam of the 25 can body.

The hollow spindle 13 is endwise slidable 30 and rotatable on a stationary stem 22 which passes through the axial bore of the spindle and has secured on its lower end a die head 23 turned to fit the upper surface of the can cover. Against this head 23 the upper end 35 of the can with its cover is held, by a means to be described later, while the operation of seaming is performed by the rollers 19 carried around it by the rotating head 17. The upper end of the support stem 22 is secured 40 against either endwise movement or rotation by its attachment in a bracket 24 secured to and projecting upward from the cover of the bearing 16 of the casing 15 which carries the roller bearings of the rotatable head 45 spindle 13.

Rotatable on the lower end of the support stem 22, between a shoulder thereon and the die head 23, is a check plate 25, each end of which is slotted to receive the rectangular stems 18 which carry the seaming rollers. The lower ends of these stems 18 are grooved, 50 as at 26, to fit the slotted ends of the check plate 25 and prevent those stems from moving upward when the rotating head 17 is 55 lifted. Being so restrained, when the head 17 is lowered or raised the stems 18 are moved inward or outward by the angle of the wedge, to or from the axis of the spindle, to press the rollers into forming contact with 60 the flanges of the can body and its cover or to withdraw them from such contact.

To facilitate adjustment of the seaming rollers 19 from the axis of rotation of the head 17 in which they are carried, the studs 65 on which each roller 19 rotates is integral

with or secured in a block 48 which has a dovetailed recess to receive the correspondingly shaped end of the stem 18, and adjustment in this dovetailed recess to and from the axis of the head is effected by a screw.

The cylindrical roller bearing casing 15 which, as stated, is vertically movable in its bearing 16 in the frame 2 of the machine, is checked against rotation by a key 27 secured in a keyway cut in the cover plate of the bearing and projecting downward to engage one of the notches of the lower adjusting nut of the bearing 16.

The bearing casing 15 of each spindle is lowered or lifted to lower or lift its rotating head by a grooved cam 28 secured on the upper part of each cam shaft 9 and 10, in the groove of which cam runs a roller 29 mounted on a stud secured in and projecting radially from the roller bearing casing 15 where it projects above its bearing 16 in the frame.

It will be noticed that in the depth of the aperture in the casing 15, through which the arc of the gear wheel 11 passes to engage the teeth cut in the hollow spindle 13 of the driving head, and in the length of these teeth, provision is made for the vertical movement of the bearing casing and of its spindle.

Secured to the lower part of the frame 2 to project from it under the rotatable seaming heads 17 is a bracket table 30, over which the can bodies are fed and from which they are successively moved from the line of delivery to the first and second seaming heads, 95 and thereafter restored to the same line for delivery from the machine. These successive movements are imparted to the cans by a turret 31 rotatably mounted in the bracket table 30, which turret has in its periphery 100 semicircular recesses 32 corresponding to the diameter of the can bodies, and spaced apart that the space between alternate recesses will correspond with that of the rotating head spindles.

The cans as fed into the recesses are retained therein during movement to and from the seaming heads by an arc shaped fence 33 approximately corresponding to the circular path of the outer sides of the can bodies.

An intermittent movement corresponding to the space of the recesses apart is imparted to the turret by a Geneva movement. This movement comprises a move and lock wheel 34 secured on the stem 29 of the turret where it projects below its bearing in the bracket 30. This wheel 34 has driving notches 35 between each of its locking recesses 36. It is rotated by a pin 38 projecting from the face of a gear wheel 37 and is locked by a concentric segment 39 projecting from the same wheel 37 to engage at each revolution one of the locking recesses 36 of the wheel 34.

In the teeth of the wheel 37 mesh those of a gear wheel 40 secured on the lower end of the cam shaft 10.

In axial alinement below each rotatable 5 seaming head a can body lifting plunger 41 is endwise movable, but not rotatable, in a suitable bearing provided in the table bracket 30. These plungers are designed to lift the can bodies into the plane of action 10 of the rollers 19 of each seaming head, and to lower them after the operation of seaming by each head is completed. This lifting movement is effected by a grooved cam 42 secured on the lower end of each cam shaft 15 9 and 10, into the groove of which cam projects a roller 43 rotatably mounted on a stud secured in and radially projecting from the plunger 41.

That the lifting contact of the plunger 20 may be cushioned to give an even pressure on the can body the lifting plunger 41 is bored to receive a cap 44 with a solid rubber ring 45 or other resilient material interposed between the underside of the cap and 25 a washer 46, which washer is adjustable by set screws through the bottom of the hollow plunger. The required initial compression is imposed on the cushion spring 45 by a central stem 47 secured in the contact head 30 and slidably passing through the adjusting washer and the bottom of the plunger, against which the outward movement of the stem is limited by a nut threaded on it.

The can bodies are fed to the machine 35 and are delivered from it on the same two parallel conveyer chains 70 which pass around two driving sprockets 71 mounted on the side of delivery from the machine and over carrying sprockets mounted on a floor 40 standard adjacent the side of delivery to the machine.

These chains 70 run in channels in the bracket table 30 which is laterally extended at the feed side to support the spacing 45 mechanism 68. The driving sprockets 71 are secured on a shaft 72 which is itself driven by a sprocket chain 73 taking over a sprocket 74 on the shaft 72 and a smaller sprocket 75 integral with a pinion 76, which 50 sprocket and pinion are together mounted on a stud 77 and driven by a gear wheel 78 secured on the first motion shaft 3 of the machine.

Spacing of the can bodies to the turret 55 is effected by any suitable device that will deliver the cans at regular distances apart corresponding to the space between the can body recesses 32 of the turret. The device 60 68 here shown is one used in other machines of the class and is covered by an earlier Patent #854,075 granted May 21, 1907. It is driven by suitable gearing from the cam shaft 9.

At the spacing device 68 the cans pass be- 65 tween a fixed fence 79 projecting upward

from the bracket table 30 and an opposite yielding fence 80 which is pivoted to the same table 30 at 81 adjacent the turret to yield outward against the resistance of a spring 83. This yielding fence is designed 70 to prevent injury to the can bodies if the spacing device should engage a can adjacent its cross diameter between the fences so as to cause a spacing finger to over-ride a can.

The covers to be applied to the can body 75 are carried in an open cage magazine 50 on a bracket 49 secured to and projecting upward from the front of the table bracket 30 to carry the can covers over the path of the can body recesses of the turret, and between 80 the bottom of this magazine and the plane of the can cover tops is a cover carrying plate 60 which is apertured at 61 to correspond in space with the recesses of the turret to which the cover plate is secured to rotate 85 with it. The tier of covers in the magazine rest upon the curved inner edges of two opposed levers 51 which are pivoted at 52 to the bracket 49 which supports the magazine, and are moved apart to release a cover by a 90 short double-ended lever 53 secured on a short pivot shaft 54 mounted in the bracket. The ends of this lever 53 are link-connected at 55 to the release levers 51.

In order that the release of a cover may be 95 coincident with the delivery of a can body to the turret, a short lever secured on the pivot shaft 54 is connected by a link rod 58 to the short arm of a bell crank 56 pivoted at 57, the longer arm of which bell crank is shaped 100 to project normally under the action of its spring 59 into the path of the cans past the spacing device, so that when a can body passing the end of the bell crank lever pushes that lever back that backward movement 105 opens the opposed levers 51 and permits a cover to fall into one of the apertures 61 of the cover carrying plate by which it is carried by successive movements until the can body which effected its release is under the 110 rotatable head by which the cover is to be seamed, when the body is lifted up by the plunger 41 through the aperture of the cover plate and lifts the cover into contact with the die head 23 against which it is held while 115 the edge of the cover which sustained it on the upper side of the aperture of the plate 60 is bent over and closed against the body of the can.

Axially slidale in each support stem 22, 120 is a knockout stem 62 which is provided with a flat head at its lower end, which flat head fits into a recess in the die 23. Mounted in a suitable head in the upper end of this stem 62 is a roller 63 with provision in a guide 125 stem 65 to prevent rotation of the stem, which roller runs in a groove of a cam 64 secured on the upper end of each cam shaft 9 and 10, the groove of the cam being adapted to impart the required vertical movement of 130

the stem. This device performs the following services in connection with the seaming of the cover on the can body. It is pressed down on the cover in the apertures of the 5 cover plate 60 as soon as rotation of the turret brings one under the seaming head spindle and steadies that cover while the can body is being lifted up against the die 23 by the operation of the plunger 41 previously 10 described. As the can body is lifted the knockout stem recedes with it into the recess provided for it in the lower face of the die 23 against which the cover is firmly held by the plunger during the operation of seaming: Again, as the seaming operation rolls the edges of the cover and body against the edge of the die 23 which fits the recess of the can cover, the seamed can requires to be forcibly expressed from the die head 23 when 15 the operation is completed, and this forcible expression is effected by the cam 64 acting on the knockout stem 63 which delivers the can body below the level of the can cover carrying plate 60 and returns, so that the 20 turret is free to rotate and carry the can to the subsequent operations.

I claim—

1. In a machine of the class described wherein the seaming of the covers on the 30 cans is performed in two operations under separate seaming heads, the combination with a suitable frame supporting the seaming head spindles, of a first motion shaft through which power is applied to the machine, an intermediate vertical shaft driven from the first motion shaft, means for simultaneously driving the vertical seaming head spindles from the intermediate shaft at a greater speed of rotation than that of 35 the intermediate shaft, a cam shaft parallel and adjacent to each seaming head spindle to coöperate with the same, means for simultaneously driving the two parallel and adjacent cam shafts from the intermediate 40 shaft at a less speed of rotation than that of the intermediate shaft, means for raising and lowering the seaming heads, means for transferring the can bodies from the line of feed to beneath the seaming heads and for 45 restoring them to the same line of feed, and means for lifting the can bodies from the plane of feed to bring their covers to the plane of seaming and for lowering them 50 therefrom.

55 2. In a machine of the class described wherein the seaming of the covers to the cans is performed in successive operations under separate seaming heads, the combination with a suitable frame for supporting 60 the seaming head spindles and the several mechanisms of the machine, a horizontally disposed first motion shaft through which power is applied to the machine, means for operating the can feed from the first motion 65 shaft, an intermediate shaft driven by said

first motion shaft parallel and adjacent the seaming head spindles, means for rotating the seaming head spindles from the intermediate shaft at a higher speed of rotation than that of the intermediate shaft, a cam shaft parallel and adjacent each seaming head spindle, means for driving said cam shafts from the intermediate shaft at a lower speed of rotation than that of the intermediate shaft, means on each cam shaft for raising and lowering its adjacent seaming spindles, means on each cam shaft for lifting a can body up to each seaming head, means on one cam shaft for operating the means for transferring a can body from the line of feed to a position under each seaming head, and for returning the can body after seaming to the original line of feed and means on the other cam shaft for operating the can body spacing mechanism. 70 75 80 85

3. In a machine of the class described, having a hollow spindle which is rotatably mounted in a suitable frame and susceptible of vertical movement in relation thereto, said spindle carrying a seaming head at 90 its lower end, a central stem secured at the upper end to the frame of the machine and passing axially through the spindle, said stem having a die head secured at its lower end adapted to fit within the cover of the 95 can, seaming rollers rotatably mounted on stems which are slidable in outwardly angled slideways on opposite sides of the seaming head, means for preventing rotational movement of the seaming roller stems, means for raising and lowering the hollow 100 spindle and its seaming head, and means connected to the central stem for preventing rise and fall of the seaming roller stems while permitting their radial movement to 105 and from the axis of rotation of the seaming head spindle.

4. In a machine of the class described for seaming covers on cans, the combination with a suitable frame, of a seaming head having a hollow spindle rotatably mounted in the frame and susceptible of vertical movement in relation thereto, a stem passing axially through the spindle and secured against endwise or rotational movement in 110 relation to the frame, stems slidably mounted on opposite sides of the seaming head in slideways which are angled outward and downward from the axis of the spindle, each stem having a seaming roller rotatably mounted at its lower end on a substantially vertical axis, means rotatable with the head and on the central stem for preventing vertical movement of the stems which carry the 115 seaming rollers. 120 125

5. In a machine of the class described, the combination with a seaming head the spindle of which is rotatably mounted in a suitable frame, stems mounted in the seaming head in slideways which are angled outward 130

from the axis of the seaming head, each stem having a seaming roller rotatably mounted on its lower end on an axis which is substantially parallel to the axis of the 5 seaming head, means for endwise moving the stems of the seaming rollers in their slideways, and means preventing rotation of the stems in the same.

6. In a machine of the class described, the 10 combination with a seaming head the spindle of which is rotatably mounted in a suitable frame, stems rectangular in cross section slidably mounted in the seaming head in slideways angled downward and outward 15 from the axis of the seaming head each stem having a seaming roller rotatably mounted on its lower end on an axis which is substantially parallel to that of the seaming head, and means for endwise moving the seaming 20 head stems in relation to the seaming head.

7. In a machine of the class described, the 25 combination with a seaming head the spindle of which is rotatably mounted in a suitable frame, stems slidably mounted in slide- 30 ways at an angle to the axis of the seaming head, each stem having a seaming roller rotatably mounted on its projecting end on an axis which is substantially parallel to the axis of rotation of the head, and means for endwise moving the stems of the seaming rollers in the slideways.

8. In a machine of the class described, the 35 combination with a seaming head the spindle of which is rotatably mounted in a suitable frame, stems mounted in slideways of the seaming head that are angled to the axis

of rotation of the head, spring cover plates retaining the stems in the slideway, a block adjustably secured to the lower end of each slideway stem, seaming rollers rotatably 40 mounted on the block, and means for imparting endwise movement to the stems in the slideway.

9. In a machine of the class described, the 45 combination with a seaming head, the spindle of which is rotatably mounted in a suitable frame, stems mounted in the seaming head in slideways which are angled outward from the axis of the seaming head, each stem having a seaming roller rotatably 50 mounted on its lower end, means for endwise moving the stems of the seaming rollers in their slideways, means preventing rotation of the stems in the same and resilient means for retaining the stems in the slide- 55 ways against outward radial movement therefrom.

10. In a machine of the class described, the 60 combination with a seaming head the spindle of which is rotatably mounted in a suitable frame, stems mounted in the seaming head in slideways which are angled outward from the axis of the seaming head, each stem having a seaming roller rotatably 65 mounted on its lower end on an axis which is substantially parallel to the axis of the seaming head which axis of rotation is adjustable in its radial distance from the axis of the seaming head.

In testimony whereof I affix my signature. 70

FRANK W. BURPEE.
